UNITED STATES PATENT OFFICE.

ROBERT SCHEIFLEY, OF PHILADELPHIA, PENNSYLVANIA.

DESIGN FOR A TOY.

SPECIFICATION forming part of Design No. 28,906, dated June 21, 1898.

Application filed March 22, 1898. Serial No. 674,834. Term of patent 3½ years.

To all whom it may concern:

Be it known that I, ROBERT SCHEIFLEY, a citizen of the United States, residing at Philadelphia, in the county of Philadelphia and State of Pennsylvania, have invented and produced a new and original Design for Toys, of which the following is a specification, reference being had to the accompanying drawings, forming part thereof.

In the accompanying drawings, Figure 1 is an elevation. Fig. 2 is a cross-section through cylinder A, and Fig. 3 is a cross-section of the smaller cylinder B.

As shown in the accompanying drawings, the leading or material feature of my design consists of a cylinder A and the smaller cylinder B, which latter is at right angles to and connected with said larger cylinder. The cyl-

inder A is closed at one end and is provided on its exterior surface from its closed end to a suitable point adjacent to its open end with a facing or coating representing a series of transverse rings or bands of contrasting colors, while the remaining surface is a band of some color contrasting with the colored bands or rings.

Having described my invention, what I claim as new, and desire to secure by Letters Patent, is—

The design for a toy, as herein shown and described.

ROBERT SCHEIFLEY.
